STEAM GENERATOR

Leroy M. Fink, Union, N. J., assignor to The Babcock & Wilcox Company, Rockleigh, N. J., a corporation of New Jersey

Application December 19, 1946, Serial No. 717,109

4 Claims. (Cl. 122—235)

1

This invention relates to improvements in steam generators.

More particularly, the invention concerns improvements in steam generators of a radiant type in which the predominating proportion of the steam is generated in closely arranged wall tubes which define the boundaries of a large volume combustion chamber.

The invention includes, in combination with the large volume combustion chamber, a superheater, economizer, an airheater, constructed and arranged in such a manner as to reduce costs of original installation and promote a high availability factor. To this end, the superheater, economizer, and airheater consist of separate banks of upright and parallel tubes disposed in succession in the gas flow rearwardly of an upright bank of tubes which constitute part of the total steam generating surface.

The invention also includes the above arrangement of installation components in succession beneath a top steel-work frame from which the upright tubes of all of the various components are successively suspended from a common datum position.

An object of the invention is to provide, in such a combination as that above indicated, a vertical tube cross-flow two-drum economizer which effectively utilizes the vertically extended space alongside a high combustion chamber.

It is also an object of the invention to provide a steam generator with the above indicated successive components arranged and constructed in such a manner that the heat exchange surfaces can be effectively maintained in good heat exchange condition because of the minimization of horizontally inclined surfaces upon which deposited solids can collect.

It is a further object of the invention to provide a steam generating installation of the above indicated type constructed and arranged with a wide dust hopper below both the economizer gas outlet and the airheater air inlet so as to provide ample gas turning space and thereby give the installation a low draft loss characteristic while providing for the gravity separation of dust particles from gases for collection in, and periodic discharge from, a single hopper.

It is also an object of the invention to provide, in a steam generator having an economizer and airheater construction which markedly decreases installation costs, increases the accessibility of the tubes, and improves maintenance conditions. Installation costs are minimized by a construction and arrangement of the steam generator

2

components which decreases the required amount of tube bends and requires a minimum amount of thermal insulation for the installation.

Further objects of the invention include the provision of a steam generator installation which facilitates cleaning of the tubes and their replacement when necessary.

The invention will be described by reference to the accompanying drawings in which a preferred embodiment of the invention has been illustrated.

In the drawings:

Fig. 1 is a vertical section through the steam generator installation, showing the arrangement of the combustion chamber, upright banks of steam generating tubes, superheater, economizer, and airheater;

Fig. 2 is an enlarged vertical section of part of the installation, particularly showing the relationships of the tubes in the economizer construction, with its multiple gas pass provisions. This figure also shows the relationship of the economizer to the superheater and the airheater. This figure further indicates the manner in which the successive components of the installation are arranged and suspended in succession from a common datum position and supported by a top frame of the heavy steel-work supporting the pressure parts of the installation;

Fig. 3 is a sectional plan of one-half of the symmetrical installation on line 3—3 of Fig. 1;

Fig. 4 is a view in the nature of partial plan showing the arrangement of the drums, headers and tubes to the top steelwork and the pressure part suspension means; and

Fig. 5 is a diagrammatic view illustrating the construction and operation of the air preheater.

In steam generating installations, and more particularly installations of high capacity for operating electric power stations, reliability of operation, or a high availability factor, is of paramount importance, and those skilled in the art will readily appreciate the prior art problems which have arisen from unclean heat exchange surfaces. These problems have been of particular concern with reference to economizer construction and operation. In many cases collections of solids from furnace gases upon the economizer tubes have not only involved high maintenance costs occasioned by the periodic removal of such solids, but have resulted in ultimate loss of efficiency of absorption capacity of the tubes between tube cleaning operations. These difficulties and others have resulted, in many cases, from the use of complicated economizer

structures in which the tubes have had thereon a multiplicity of elements providing surfaces on which undesired deposits were made. The present invention avoids such difficulties by providing a simplified construction eliminating a multiplicity of tube bends in the original construction and enhancing maintenance by its increased accessibility of the tubes for cleaning or replacement.

The economizer 10 is shown in Fig. 1 cross baffled at 12 and 14 for the transverse flow of furnace gases across the tubes in gas passes 16, 18 and 20 of large free flow area. The cross baffles are steeply inclined, and for long life they are supported and cooled by some of the economizer tubes. For example, the upper cross baffle 12 of the economizer is supported upon the inclined mid-portions 22 of the front tubes of the economizer and is extended forwardly from a position 24 in the economizer bank. The front economizer tubes extend along the baffled position and then downwardly along the front wall 26 of the economizer to the lower economizer drum 28. The upper parts 30 of these tubes extend forwardly from the upper economizer drum 32 and downwardly to a position adjacent the superheater to support and maintain the refractory and thermal casting insulation shown at 34 and 36.

The upper cross baffle 12 of the economizer is also so arranged as to constitute a substantial continuation of the downwardly inclined wall 40 beneath the superheater 42. This wall is cooled and supported by the downwardly inclined sections 44 of the rear row of steam generating tubes which constitute circulators connecting the main steam and water drum of the installation with the submerged drum. These tubes also have upper roof sections 46 extending rearwardly over the superheater to a position adjacent the upper parts 30 of the front row of economizer tubes adjacent the upper economizer drum 32. From that position mid-portions 48 of the circulators extend downwardly toward the upper economizer baffle 12.

With this construction the heating gases pass through the upper part of the economizer to a position rearwardly of the main bank 50 of economizer tubes where ample space is provided for the turning of the gases rearwardly of the main bank of economizer tubes and forwardly of the rear row 52 of the economizer tubes which are disposed vertically between the air heater 54 and the economizer above the lower cross baffle 14 of the economizer. From this position intermediate sections 56 of these tubes are inclined downwardly to afford fluid cooling elements and supports for the lower economizer baffle 14. This baffle consists of appropriate refractory material closing the spaces between the tube sections 56 and extending downwardly at a sharp angle of the order of the inclination of the upper economizer baffle 12.

The gas turning space at the rear of the first economizer gas pass 16 is continued to a position just above the lower economizer cross baffle 14 and at the entrance of the second economizer pass 18, in the interests of low draft loss.

Below the lower economizer cross baffle 14, ample gas turning space is provided at 60 for the gases turning from the outlet of the second economizer gas pass 18 to the inlet of the third gas pass 20, this turning space being provided by the spacing of the lower sections 62 of the front row economizer tubes considerably for-

wardly of the main bank 50 of economizer tubes.

From the gas turning space 60 below the upper economizer cross baffle, gases pass rearwardly over the lower sections of the economizer tubes 5 and into the lower gas turning space 64 beneath the lower economizer cross baffle. From this turning space the gases pass downwardly to a position above the large dust hopper construction 66 which extends entirely across the gas outlet 10 68 of the economizer as well as the gas inlet 70 for the air heater. In this gas turning space, several factors contribute to the separation of suspended solids from the furnace gases. One of these is the downward flow of the gases from 15 the last economizer pass into the dust hopper. A second is the change in direction of the gases in the ample turning space provided in the dust hopper construction, and a third factor is the further turning of the gases as they move to 20 process to pass upwardly through the tubes of the air heater.

The air heater 54 consists of a bank 72 of upright and horizontally spaced tubes fixed at their lower ends to a lower tube sheet 74 and at their 25 upper ends to an upper tube sheet 76 at a position close to the upper rectangular frame 78 of the steel-work. Appropriate transverse baffles 80-83 (Fig. 5) across said tubes provide for air flow in the multiple passes 85-90 externally of 30 the tubes for the purpose of effectively heating air to be delivered to the furnace or combustion chamber.

The economizer and air heater are separated by the common wall 92 closely adjacent the rear 35 tubes 52 of the economizer and the front tubes of the air heater as clearly indicated in Fig. 2. Thus, a marked simplicity in construction is attained with attendant decreased upkeep and in 40 original installation costs the wall 92 being cooled by the economizer tube 52, on one side, and by the front row of air preheater tubes on the other side.

It is to be noted that the top tube sheet 76 of the airheater is disposed at a position adjacent the rectangular top frame 78 of the steel-work. As indicated in Fig. 1, this tube sheet is in 45 position to be directly secured to rearwardly disposed beams (such as the beam 94 (Fig. 1)) of the top frame work which are disposed in the 50 same horizontal zone with horizontally disposed and fixed top frame of the steel work for supporting the economizer, superheater and the steam generating tubes.

Just forwardly of the economizer are shown a 55 series of suspension rods (Figs. 2 and 4) 100-109 by which the tubes, headers and other pressure parts of the superheater construction are supported from the auxiliary beams of the top frame. The economizer is similarly supported by the 60 drum straps 114. Forwardly of the superheater suspending structures are the heavy U-shaped drum straps 116 for supporting the steam and water drum 118. These extend upwardly through the top frame work components such as 120, 65 of heavy construction.

Forwardly of the steam and water drum 118, there are a number of suspension rods (not shown) for similar suspension of the headers, tubes and other pressure parts of the combustion 70 chamber 130 section of the installation.

Thus, the pressure parts of the combustion chamber, upright bank of steam generating tubes 132, upright banks of superheater tubes, economizer, and airheater, are top suspended from a 75 unitary frame at the top of the steel-work. In

this manner, not only are expansion and construction problems simplified, but maintenance problems and costs are materially reduced.

The combustion chamber illustrated in the drawings is of a height of the order of 100 feet. Its other dimensions being indicated by the proportions of Fig. 1. The lower part of the combustion chamber involves a hopper construction 134, the downwardly converging hopper walls 136 and 137 of which are defined by the lower sections of the front and rear wall steam generating tubes 140 and 142. Alternate tubes at their lower ends are bent downwardly to the positions indicated at 150 and 152 and are connected to the lower headers 154 and 156 which in turn are in communication with the water space of the steam and water drum 118 through the agency of suitable tubular connections not shown.

The steam space of the steam and water drum 118 is in communication with the superheater 42 through the agency of a series of tubes having roof sections such as 160 and 162 leading horizontally to a position toward the rear of the superheater where they have vertical sections such as 168, downward extensions of which constitute the rear tubes 170 of the superheater. From this position at the rear of the superheater, the steam flow from these tubes continues through connections including the successive multiple loop return bend tube sections 180-188 which lead to the rearward upper (and intermediate) superheater header 200. The flow is upward through the upright tube sections 180, 182, 184, 186, and 188, and downward through the alternately disposed sections 181-183, 185 and 187, it being understood that these sections are serially connected at their upper and lower ends by the return bends 190-198. With this construction, the tubular sections 188 act as pendant supports from the header 200, with this part of the superheater balanced on either side thereof. From this header, the steam flows through appropriate connections to an attemperator and returns from the attemperator to the header 202. From the superheater header 202, the steam flows successively through the similar upright tubular sections 210-213 which are disposed as a bank of tubes, just rearwardly of the access space 214. These tube sections are connected for continuous steam flow by the return bends 220-222. Beyond this position, the steam flow is through the wide return bends 230, and then successively through the upright tube sections 230-233, connected for series flow by the return bends 236-238, these elements constituting the forward bank 240, of superheater tubes, pendants supported through the hangers 103, the header 242 and the tube sections 233. From the header 242 the steam flows to a point of use.

The illustrative arrangement of the steam generator installation components minimizes the refractory material and thermal insulating material required for casing construction, and further reduces original installation costs by the simplification of the casing construction. For example, the successive elements such as the superheater, economizer, and airheater tubes are arranged alongside each other and in parallel vertical positions so that a minimum of refractory material is required between those successive components. Again, the construction of the economizer is such that its baffles require a minimum of refractory material. Thirdly, the disposition of the various steam generating installation components described above in successive vertical positions sim-

plifies the casing construction at the top of the installation and materially reduces the amount of refractory material and thermal insulation material required at that position. These factors are not only of importance with respect to the original installation costs, but they are also of considerable importance with respect to subsequent maintenance in which access must frequently be had to the tubes of the components of the installation. In such cases, and when the construction and arrangement of the components is such that a minimum amount of casing materials is required, the amount of such materials to be removed and replaced for repairs on any single component are obviously markedly reduced.

The arrangement of the components of the illustrative installation is also such as to afford the optimum use of a given horizontal area. This not only results from the closely arranged banks of vertical tubes which constitute the different components, but also from the particular construction of the combustion chamber 130 which permits the disposition of the vertical bank 25 of steam generating tubes 132 and a substantial part of the superheater surface within the upwardly extended confines of the main part of the combustion chamber. This point will be clear from an inspection of Fig. 1 wherein the upper part 250 of the combustion chamber forwardly of the bank of tubes 132 is much narrower than the ignition zone of the combustion chamber adjacent the burners 252-254. The upper parts 256 of the rear wall tubes 142 are upwardly inclined toward front wall tubes 140, and these parts extend inwardly for a distance greater than one-third the depth of the combustion chamber from which point they extend to a direct connection with the submerged drum 29.

The burners 252-254 are supplied with preheated air through the duct-work which includes a burner casing 258 connected with a transversely extending lower duct 260. The latter is connected on either side of the furnace by a rearwardly extending duct such as 262 with an upwardly extending duct 264 which leads to the airheater inlet 266 (Fig. 5).

Fig. 1 also discloses the upright tubular member 270 providing the attemperator chamber with its outlet connected by the conduit 272 with the intermediate superheater 202. This attemperator is preferably of a type such as that illustrated in the pending application of Fletcher and Huge, filed on August 17, 1946, S. N. 691,274, Patent Number 2,550,683.

Referring again to the economizer, its lower drum 28 is connected with a source of feed water by appropriate connections (not shown), and the upper drum of the economizer is in communication with the steam and water drum 118 by the tubular connections 280 and 282. These connections preferably lead to a drum inlet chamber from which the steam and water mixture passes to steam and water separating devices from which steam and water separately pass to the respective steam and water spaces of the drum. Such an inlet chamber associated with such steam and water separating devices is indicated in Fig. 2 of the U. S. patent to Fletcher et al., 2,271,634, February 3, 1942.

With reference to the circulatory connections for such a steam generator as that shown in the drawings, it will of course be understood that there are appropriate and preferably external tubular connections between the water space of

the drum 118 and the submerged drum 28. Similar downcomers will also connect the water space of the drum 118 with the lower headers for the wall tubes of the combustion chamber, such headers as those shown at 154 and 156. The lower headers for the combustion chamber wall confronting the observer in Fig. 1 of the drawings are indicated at 290, 292, and 294 at the lower part of this figure. It will also be understood that the tubes of this wall may be connected to a similar header or headers at a level above that of the combustion chamber and that these top headers may be in communication with the steam and water inlet chamber of the drum 118 by appropriate circulators.

The economizer tubes of the main bank of tubes 50 are arranged in front to rear rows as indicated in Fig. 3. This enhances the functioning of the soot blowers 300—303 (Fig. 2), the jets of which are aligned with the spaces between the rows of tubes. The general downflow of gases and the arrangement of upright tubes also further enhance the removal of solids from the tubes by the action of the soot blower jets. The larger gas turning spaces on either side of the main bank of economizer tubes as well as the cavity between the superheater and the economizer further improve the removal of solids from the tubes by the soot blower. These spaces also facilitate access to the tubes, and to take advantage of this construction large access doors are provided as indicated at 310—313.

I claim:

1. In a steam generating installation of high capacity, upright and closely arranged steam generating wall tubes constructed and disposed to define boundaries of a vertically elongated combustion chamber, steelwork including a top frame above the combustion chamber, a steam and water drum suspended from said frame and having said tubes connected thereto, said combustion chamber having a lateral gas outlet leading to a rearwardly tapering gas pass at a level below that of the drum, a submerged drum, a steam generating convection section including upright tubes extending across said gas pass and directly connecting said steam and water drum and said submerged drum, a superheater including a bank of upright multiple-loop tubes disposed transversely of the gas flow in said gas pass, superheater headers, means suspending the superheater headers and tubes from said frame, circulator tubes connected to said drums and extending around the superheater in vertical planes and having sharply downwardly inclined portions disposed beneath the superheater and leading toward the submerged drum and combining with baffle forming material to define the lower boundary wall of said rearwardly tapering gas pass, a two drum bent tube economizer including long upright tubes extending from an upper position near the level of the top of the convection section and the superheater to a position below the level of the superheater, the upright extent of the economizer being a substantial part of the height of said combustion chamber and the entire installation, an air heater including long upright tubes disposed in a bank in parallelism with the economizer tubes and of a vertical extent of the order of that of the economizer, the main part of said economizer bank being spaced substantially rearwardly of said superheater and substantially forwardly of the air heater to present cavities at said positions of spacing, front tubes of the economizer bank

28. having intermediate parts inclined sharply downwardly in a substantial continuation of the inclined parts of said circulator portions and supporting an upper cross-baffle for the economizer, said upper cross-baffle extending over a gas turning space in front of the economizer bank and terminating forwardly of the rear of the economizer to separate the first two cross passes (gas) of the economizer, the upper cross-baffle disposed as a substantial continuation of the lower boundary wall of the tapering gas pass, rear tubes of the economizer having upper parts spaced rearwardly of the main part of the economizer bank extending downwardly alongside the air heater to a level intermediate the level of said cross-baffle and the level of the lower economizer drum and then having sharply downwardly inclined parts extending from that position forwardly to the main part of the economizer bank, baffle forming material supported by said last mentioned inclined parts to form an economizer lower cross-baffle, and a dust hopper extending across the gas outlet of the economizer and the gas inlet of the air heater.

2. In a vapor generating installation of the type having heating gases passing from a combustion chamber across and externally of the spaced upright tubes of a convection vapor generating section, a vapor and liquid drum to which the upper ends of the tubes are connected, and a submerged drum connected to the lower ends of the tubes; the combination therewith of a convection superheater including multiple loop upright tube sections disposed in a bank rearwardly of the convection section, fluid circulators directly connecting said drums and extending around the superheater in vertical planes with their lower portions sharply inclined downwardly beneath the superheater toward said submerged drum and disposed in wall alignment, a main bank of upright economizer tubes spaced rearwardly of the superheater and having their upper portions forming an upright gas flow screen subject to a continuation of the gas flow from the superheater, upper and lower economizer drums to which the economizer tubes are directly connected, the economizer also having a rear row of upright tubes with parts spaced substantially rearwardly of said main bank of tubes near its upper portion and having their intermediate portions sharply downwardly inclined toward a position intermediate said main bank to constitute a support for a lower economizer cross-baffle, said tubes extending alongside the tubes of the main bank below said cross-baffle, others of said upright economizer tubes having portions sharply inclined downwardly and forwardly of said main bank to constitute supports for an upper economizer cross-baffle, the lower parts of the latter tubes being spaced substantially forwardly of the main bank of economizer tubes to provide a gas turning space of large volume at the outlet of the second gas pass of the economizer and inlet of the third gas pass below said lower baffle, an air heater including a vertically elongated bank of tubes disposed alongside the upright economizer tubes, and a dust hopper below the economizer gas outlet and air heater gas inlet.

3. In a vapor generating unit of the type having means constituting a source of heating gases, a superheater and an air heater; the combination therewith of a fluid heating component of said unit interposed relative to the air heater and superheater and having upper and lower drums

and a bank of upright tubes directly connecting said drums and disposed in the path of said gases, first wall means extending upwardly from said lower drum adjacent the forward side of said bank and terminating in downwardly spaced relation to said upper drum to form the lower limit of a gas inlet into said bank from the superheater, and second wall means extending downwardly from said upper drum along the front surface of the air heater and adjacent the rearward side of said bank and having a part terminating in upwardly spaced relation to said lower drum to separate lower cross tube gas passes leading to a gas outlet from the air heater, each of said wall means having a portion substantially spaced from the majority of tubes of said bank to form a wall of upper and lower substantially unobstructed gas turning spaces opposite said inlet and said outlet respectively, said second wall means having a part terminating within said bank in a lower end portion inclined downwardly toward said lower gas turning space, said bank of tubes including a forward row of tubes having intermediate portions inclined forwardly from the majority of tubes of said bank and disposed along an intermediate inclined portion of said first wall means in cooling and supporting relationship thereto, said bank of tubes also including a rearward row of tubes having intermediate portions inclined upwardly and rearwardly from the majority of tubes of said bank and disposed along said inclined portion of said second wall means in cooling and supporting relationship thereto, said tubes in said rows having end connections to said drums at the same side of said bank from which said tubes are respectively inclined.

4. In a vapor generating unit of the type having means constituting a source of heating gases, a superheater and an air heater; the combination therewith of a fluid heating component of said unit interposed relative to the superheater and the air heater and having upper and lower drums and a bank of upright tubes directly connecting said drums and disposed in the path of said gases, first wall means extending upwardly from said lower drum at a position forwardly of the main part of said bank and terminating in downwardly spaced relation to said upper drum to form the lower limit of a gas inlet into said bank from the superheater, and second wall means extending downwardly from said upper drum along the front surface of the air heater

and adjacent the rearward side of said bank and having a part terminating in upwardly spaced relation to said lower drum to separate lower cross tube gas passes leading to a gas outlet from the lower part of said bank to the air heater, each of said wall means having a portion substantially spaced from the majority of tubes of said bank to form a wall of upper and lower substantially unobstructed gas turning spaces opposite said gas inlet and said gas outlet respectively, said second wall means having a part terminating within said bank in a lower end portion inclined downwardly toward said lower gas turning space, an upright flat metal air heater wall constituting a part of the second wall means, said bank of tubes including a forward row of tubes having intermediate portions inclined downwardly and forwardly from the majority of tubes of said bank and disposed along an intermediate inclined portion of said first wall means in cooling and supporting relationship thereto, said bank also including a rearward row of tubes having intermediate portions inclined upwardly and rearwardly from the majority of tubes of said bank and disposed along said inclined portion of said second wall means in cooling and supporting relationship thereto, the rearward row of tubes including parts extending in wall cooling relationship along said upright flat metal wall, said tubes in said rows having end connections to said drums at the same side of said bank from which said tubes are respectively inclined.
